UNITED STATES PATENT OFFICE.

JOHN E. DAVIS, OF BROOKLYN, NEW YORK.

SOUND-AMPLIFYING MEANS.

Application filed August 26, 1925. Serial No. 52,481.

This invention relates to means for amplifying sound waves, and is particularly adapted for use in the amplifying of sound waves emitted by the vibration of a diaphragm of a sound reproducing device, the present invention being a further improvement of the sound amplifying means disclosed in my co-pending application Serial No. 688,714, filed Jan. 26, 1924, wherein there is provided a receiver for sound waves connected to and supported from a sounding board extending around the receiver and being in the nature of a resonance chamber of truncated conical form and rectangular in cross section, or of truncated pyramidal form, closed at the smaller end, and said receiver and sounding board being made of panels of relatively thin wood, such as spruce, having alternate relatively hard and soft or spongy growth rings quarter sawed across the natural growth rings whereby said growth rings or the grain extend in parallel and alternate layers and the panels secured together at the longitudinal edge portions. The sound waves transmitted into the receiver set up a vibration of the wall of said receiver which vibrations, through the support and connection of the receiver with the sounding board, are transmitted to the sounding board not only vibrating the sounding board in consonance therewith but also absorbing distorted vibrations induced by sound waves of overtones, and magnifying the sound waves of dominant and undertones.

It is the object of the present invention to improve the construction and arrangement of the sound receiver and resonance chamber or sounding board whereby there will be a minimum resistance to the vibration thereof.

In carrying out the invention the resonance chamber or sounding board is constructed of panels the same as in my application hereinbefore referred to but instead of connecting the panels with the longitudinal edge portions in contact for the entire length thereof they are secured together at such edge portions adjacent the ends only with the intermediate portions cut away and thus providing spaces between said edge portions of the panel.

The panels of the sound receiver are secured together at the longitudinal edge portions adjacent one end only, to constitute the sound receiving end, and said edge por-

tions from said connecting portion being free and out of contact to the opposite end, and by which portion of the receiver panels the receiver is connected to and supported from the sounding board.

In the drawing accompanying and forming a part of this specification there is shown an embodiment of the invention wherein Figure 1 is a longitudinal sectional view of my improved sound amplifying means and showing the manner of mounting the same in a cabinet; and

Figure 2 is a perspective view with the cabinet partly removed and broken away.

The embodiment of the invention illustrated in the drawing comprises a truncated cone shaped chamber 3, preferably of rectangular shape in cross section, forming in effect a truncated pyramidal resonance chamber, the wall of which is in effect a sounding board, which chamber is constructed of panels, preferably of wood having alternating relative hard and soft spongy growth rings, spruce being preferred and having been found to function efficiently for the purpose. It is understood that other wood having the same growth characteristic may be utilized. The wood is quarter sawed or sawed across the growth rings whereby the grain will extend in parallel relation longitudinally of the panels, and in the structure of the resonance chamber said grain will extend longitudinally of the axis thereof. The panels of said chamber are secured together practically without stress or strain and to offer a minimum resistance to the vibration thereof. For this purpose the longitudinal edge portion of the panels within the ends thereof are cut away and the panels are connected together at adjacent opposite ends, as at 4, with the intermediate portions of the panels free and out of contact, the cut away portions forming the spaces 5 between adjacent panels. The small end of said chamber is closed by a wall 5'.

A sound receiver 6, which is preferably of conical tubular or pyramidal form with the wall diverging from the receiving end 7 to the opposite end 8 and of rectangular shape in cross section, is mounted in the resonance chamber or sounding board 3 to extend thereinto from the larger end to adjacent but in spaced relation to the closed end 5', the receiving end of the sound receiver 6 being at the larger open end of the resonance

chamber 3 with the latter extending around and in spaced relation to the receiver 6 as clearly shown in the drawing. The receiver 6 is also made of panels secured together 5 at the longitudinal edges at the inlet or receiving end 7 only, as at 9, with the marginal edge portion cut way or under cut from the connecting portion to the end 8 whereby said edge portions will be in spaced 10 relation, as at 10, and said marginal edges of the panels free. The receiver 6 is also made of wood having a grain consisting of alternating hard and soft or spongy layers extending longitudinally thereof. 15 To transmit the vibrations set up in the panels of the receiver 6 by the transmission of sound waves thereinto to the panels of the resonance chamber 3 in the receiver is connected to and supported from the panels 20 of said chamber 3 by bridge pieces 11 engaged edgewise between the walls of the receiver 6 and resonance chamber 3 to extend longitudinally thereof and substantially 25 midway between the sides thereof, said bridge pieces having been found to function efficiently by having the same engage for the full length thereof with the receiver 6 and secured thereto, as by gluing, and having a portion cut from the opposite longitudinal edge intermediate its ends, as at 12, whereby only a relatively small part of said edge of the bridge pieces and at opposite 30 ends will engage with the wall of the resonance chamber 3. The receiver 6 and bridge pieces are held in position relative to the resonance chamber 3 substantially without stress or strain, screws 13 being shown for this purpose passing through the sounding board and engaging in the bridge pieces. 35 In order that the amplifier will function properly the amplifying unit, comprising the resonance chamber 3 with the sound wave receiver 6, is mounted in a support 40 without stress or strain for which purpose it is mounted at the outer or enlarged end of the resonance chamber 3. In the present instance it is mounted in a cabinet 14 extending around in spaced relation and closing the sides and closed end 5' of the resonance chamber and having an open end at the enlarged open end of the said chamber the latter being secured in said casing by screws 45 13 passing through the edge portion of the wall of the resonance chamber substantially midway between the sides and engaging in the casing with a cushioning member 16 interposed between the resonance chamber and casing, as clearly shown in the drawing. A grille 17 may be attached to the 50 open end of the casing and amplifier. 55 The amplifier may be used as a megaphone for augmenting and magnifying the sound of the human voice directly in which case the user talks directly into the receiving end 7 of the receiver 6. To use the de-

vice for amplifying reproduced sounds, as by a vibratory diaphragm either mechanically or electrically operated, a diaphragm carrier or microphonic unit, designated in a general way at 18, is mounted directly in 70 the receiving end of the receiver, for which purpose a reinforcement, as shown at 19, is arranged at the receiving end of the receiver, this reinforcement means consisting of a layer of wood similar to the material 75 of which the receiver is made with the grain extending longitudinally of the receiver.

While I have illustrated and described one manner of constructing and arrangement of my improved sound amplifier it 80 will be obvious that the invention is not to be limited to such construction and arrangement and that variations and modifications may be made in structure and form and that portions of the invention may be used without others and come within the scope of the invention. 85

Having thus described my invention I claim:

1. In a sound amplifier, a resonance chamber of truncated conical form comprising panels secured together at the longitudinal edge portions adjacent the ends only with the longitudinal edge portions cut away 90 intermediate said securing portions for the purpose specified. 95

2. In a sound amplifier, a resonance chamber of truncated conical and rectangular shape in cross section, the side walls of said chamber being constructed of panels having cut away portions intermediate the ends and secured together at the edge portion at the 100 ends of the cut away portions, and a closure secured to the panels at the smaller end. 105

3. In a sound amplifier, a resonance chamber of truncated conical and rectangular shape in cross section, the side walls of said chamber being constructed of panels having cut away portions intermediate the ends and secured together at the edge portion at the 110 ends of the cut away portions, and a sound receiver and support for a sound reproducer within and supported by the panels of the resonance chamber. 115

4. In a sound amplifier, a resonance chamber of truncated conical form constructed of panels connected together at the longitudinal edge portions adjacent the ends and the edge portions of the panels intermediate the connections thereof being free and out of contact to connect the panels without stress or strain, an open end cabinet, and means to mount the resonance chamber in the cabinet substantially without stress 120 or strain with the larger end thereof at the open end of the cabinet. 125

5. In a sound amplifier, a resonance chamber of truncated conical form constructed of panels secured together at the 130 longitudinal edge portions adjacent the ends

- with the edge portions of the panels intermediate the connecting portions cut away, a closure secured to the panels at the smaller end, a tubular sound receiver and support for 5 a sound reproducer extending into the resonance chamber from the larger end and centrally thereof, and bridge pieces interposed between the sound receiver and panels of the resonance chamber to support the 10 sound receiver and connect the same with the panels of the resonance chamber.
6. In a sound amplifier, a resonance chamber of truncated conical form constructed of panels secured together at the 15 longitudinal edge portions adjacent the ends with the edge portions of the panels intermediate the connecting portions cut away, a closure secured to the panels at the smaller end, a tubular sound receiver and support 20 for a sound reproducer extending into the resonance chamber from the larger end and centrally thereof, bridge pieces interposed between the sound receiver and panels of the resonance chamber to support the sound 25 receiver and connect the same with the panels of the resonance chamber, an open end cabinet, and means to support the resonance chamber without stress or strain at the larger end and with said end at the open 30 end of the cabinet.
7. In a sound amplifier, a resonance chamber of truncated conical form constructed of panels secured together at the longitudinal edge portions adjacent the ends 35 with the edge portions of the panels intermediate the connecting portions cut away, a tubular sound receiver and support for a sound reproducer, said receiver being constructed of panels secured together at the longitudinal edge portion adjacent one end and the edge portion of the panels from such connection being free to the opposite end of the receiver, and means extending longi- 40 tudinally of the receiver and resonance chamber to connect and support the receiver 45 from said chamber at the free end portions of the panels.
8. In a sound amplifier, a resonance chamber of truncated conical form constructed of panels connected together at the longitudinal edge portions adjacent the ends with the portions of the panels intermediate the connections thereof free and out of contact, a closure for the smaller end of said chamber, a conical tubular member constructed of panels connected together at the edge portions adjacent the smaller end and arranged at said end as a support for a sound reproducer, and the edge portions of the panels of said tubular member from the point of connection extending to the larger end being free and out of contact with adjacent panels, bridge pieces to support the tubular member within and from the resonance chamber with the smaller end of the tubular member at the larger end of the resonance chamber and the larger end of the tubular member adjacent the smaller closed end of the resonance chamber, said bridge pieces being arranged in edgewise relation 50 to extend longitudinally of and midway between the sides of the panels of the resonance chamber and tubular member, and means to support the resonance chamber 55 substantially without stress or strain. 70
9. In a sound amplifier constructed and arranged in accordance with claim 8, an open end cabinet in which the resonance chamber is mounted at the open end without stress or strain with said end at the open 60 end of the cabinet. 80

Signed at New York city, in the county of New York and State of New York, this 1st day of August, 1925.

JOHN E. DAVIS.
